DISPENSER

Filed Aug. 22, 1946

UNITED STATES PATENT OFFICE

2,517,206

DISPENSER

Lyle S. Houghton, Brentwood, and Kenneth W. Ellis, Webster Groves, Mo., assignors to Aleo Valve Company, University City, Mo., a corporation of Missouri

Application August 22, 1946, Serial No. 692,172

3 Claims. (Cl. 137—111)

1. The present invention relates to a dispenser. More particularly, it relates to a mechanism for the dispensing of insecticides, or the like.

It is an object of the invention to provide a valve controlled dispenser for insecticides, or the like, which may be mounted in an area to be sprayed. A particular object is to provide a dispenser having a mounting that is readily adaptable to either concealed connections or open connections. Stated differently, it is an object of the invention to provide a dispensing device of this kind having a universal mounting.

It is a particular object to provide a dispensing device of this kind having a pleasing appearance. A further object of the invention is to provide a dispenser of this kind having an enclosing cover that may be readily removed and may be eliminated where appearance is no factor. A further object is to provide a dispenser of this kind that is readily accessible for servicing. In particular, it is an object to provide a dispenser having enclosed mechanical parts which are readily accessible by the removal of a cover, and which cover may be removed by a very simple operation.

Other objects will appear from the description to follow.

In the drawings:

Fig. 1 is a side elevation of an embodiment of the invention using enclosed connections, with the mounting thereof shown in section;

Fig. 2 is a transverse vertical section through the mechanism;

Fig. 3 is a bottom view thereof; and

Fig. 4 is a side elevation of the dispensing device mounted for open connections, the latter being in section.

Referring particularly to Fig. 2, a ceiling or like mounting base is shown at 10. This base may receive an inset connection box 11 that is enclosed by a cover plate 12 attached to it removably by screws 13. Preferably, the plate 12 is flush with the lower surface of the ceiling 10. This junction box or connection box 11 is adapted to receive a line 15 for the conduction of insecticides or whatever is to be dispensed by the mechanism. It is also adapted to contain suitable electrical leads, such as 16 and 17, which are connected with a power source.

As shown in Fig. 1, the insecticide line 15 may pass out through the side of the box 11, if desired. The manner of terminating the ends of the line 15 and the wires 16 and 17 is, per se, immaterial to the present invention. These

terminations may be made in any conventional manner.

As shown in Fig. 4, the box 11 may be mounted below the surface of the ceiling 10, and attached thereto by conventional means (not shown). In this case, the insecticide line 15 and the wires 16 and 17 will lead laterally from the junction box 11 and be supported below the surface of the ceiling 10.

Referring more particularly again to Fig. 2, the insecticide line 15 leads through a fitting 20 to be connected to an elbow 21 with an integral strainer that is fastened through the side of a valve body element 22. This valve body element has a vertical bore 23 extending down from the top thereof, and affording an elevated valve seat 24. A valve passage 25 extends vertically from the valve seat 24 to a distributing point from which multiple ports 26 radiate. These ports have fittings 27 that receive nozzles 28 threaded thereonto. Thus, the device provides multiple nozzles that are as shown in Fig. 3 as comprising four nozzles directed at 90° to each other.

25 The bore 23 has a tube 30 fixed therein. This tube has a plug 31 permanently fitted and held in its top. The plug 31 has a threaded extension 32 that passes through the top plate 12 and receives suitable nut and washer arrangement 33, whereby the tube, the valve body 22, and the various nozzles are supported from the box 11.

30 The tube contains a solenoid core 35 which has a vertical passage therethrough in which a valve stem 36 reciprocates. The valve stem carries a valve head 37 at its lower end, this head being cooperable with the valve seat 24. The upper end of the valve stem 36 carries a head 38 that may seat in a socket provided in the top of the core 35.

35 The tube 30 passes upwardly through the two leg members of a U-shaped bracket 40. The upper leg member 41 of the bracket 40 is engaged by the top of the plug 31 and receives the threaded projection 32 therethrough. The lower leg member 42 has an opening large enough to receive the tube 30. By this means, the bracket 40 is supported. This bracket receives a magnetic coil 43 that is energized from the two leads 16 and 17. This magnetic coil surrounds

40 two oppositely inserted sleeves, as shown.

45 The bottom of the valve body 22 is adapted to receive a threaded plug 45. This plug projects from the bottom of the valve housing and is adapted to have a bowl-shaped cover member 46 pass over it. The cover member has suitable

50

openings 47, through which the nozzles 28 project. The upper end of the bowl member may engage the lower surface of the ceiling 10 in the mounting shown in Figs. 1 and 2. It is clamped thereagainst by a cap screw 48. Where the arrangement is that shown in Fig. 4, the cap nut 48 will cause the cover 46 to engage the bottom of the valve body, and thereby be clamped in position.

Operation

When it is desired to dispense insecticide, a suitable switch S, as illustrated diagrammatically in Fig. 2, may be closed. This will cause energization of the coil 43. This coil will act upon the core 35, causing the same to rise. As the core 35 approaches its position of maximum magnetic pull, it will engage the head 38 of the valve stem and lift the valve to an open position. This will permit the insecticide from the line 15 to flow into the bore 23, thence around the valve seat 24, and out the passage 25 to the several ports 26, whence it may be dispensed through the four nozzles 28. When it is desired to stop the dispensing operation, the switch S may be opened. This will deenergize the coil 43, and permit the core 35 to fall, carrying the valve downwardly to its closed position.

When it is necessary to service the valve parts, the cap nut 48 may be removed. This will permit the cover 46 to be withdrawn from the bottom. When the cover is removed, the entire valve mechanism is readily accessible. The valve mechanism may then be removed by separating the tube 15, disconnecting the wires 16 and 17, loosening the screws 13, and withdrawing the plate 12. The valve may be quickly disassembled by removing the nut 33 and detaching the union connector 20. When the nut 33 is removed, the tube 30, the valve body 22, and the associated parts may be slipped through the bracket 40, and thereby removed from the coil for any servicing that is necessary. Obviously, various nozzles may be applied to the fittings 27.

It will be seen that a structure has been provided which is efficient in operation, easy to service, and pleasing in appearance. Furthermore, it has a very simple mounting arrangement that is adapted for use with either exposed wiring or concealed wiring and connections.

What is claimed is:

1. A dispenser or like device, comprising an electrically operated valve unit having a valve housing with inlet and outlet means and a valve seat therebetween, a valve cooperable with said seat, electrically energized power means for operating the valve, means securing the power means and valve housing together to form the unit, an

attachment member at one end of the unit for attachment with a support, and a unitary cover for enclosing the unit, said cover having port means for the valve outlet means, and means to attach the cover to the unit.

2. A dispenser or like device, comprising an electrically operated valve unit having a valve housing with inlet and outlet means and a valve seat therebetween, a valve cooperable with said seat, electrically energized power means for operating the valve, means securing the power means and valve housing together to form the unit, an attachment member at one end of the unit for attachment with a support, and a unitary cover for enclosing the unit, said cover comprising a hollow casing adapted to fit over the unit from one end, and having port means for the valve outlet means, and attachment means between the said end of the casing and the unit.

3. A dispenser for insecticides or the like comprising a magnetic coil, a valve housing depending from and attached to the magnetic coil, whereby they may be supported together, an inlet port into the valve housing, outlet means therefrom, a magnetic core, a valve controlling flow to said outlet ports adapted to be opened and closed by operation of the magnetic core under influence of the magnetic coil, means extending from above the magnetic coil for attaching the entire device to a support, and means depending below the valve body for supporting a housing, and a housing supported on said last named means and adapted to enclose the entire device.
